UNITED STATES PATENT OFFICE.

HAROLD EDGAR YARROW, OF GLASGOW, SCOTLAND.

BURNER FOR LIQUID FUEL.

1,114,664.

Specification of Letters Patent.

Patented Oct. 20, 1914.

Application filed September 27, 1913. Serial No. 792,196.

To all whom it may concern:

Be it known that I, HAROLD EDGAR YARROW, a subject of the King of Great Britain, residing in Scotstoun, Glasgow, Scotland, and whose post-office address is Yarrow & Co. Ltd., Scotstoun, Glasgow, Scotland, have invented certain new and useful Improvements in Burners for Liquid Fuel, of which the following is a specification.

10 This invention relates to burners for liquid fuel, such for example as are used in oil-fired boiler furnaces, and has for its object to provide means whereby the angle of the cone of spray or atomized fuel delivered by the burner nozzle can be kept constant for varying rates of consumption of the liquid fuel. With this object means are provided whereby the whirling velocity of the liquid fuel can be reduced or increased in accordance with the rate of consumption of the fuel, this variation in the whirling velocity being effected either independently of, or in conjunction with, the regulation of the nozzle aperture for varying the rate of consumption of the fuel.

One apparatus embodying the present invention is shown in longitudinal section in Figure 1 of the accompanying drawings, Fig. 2 being a corresponding view of a modified apparatus, while Figs. 1^a and 2^a are corresponding views of detail features of Figs. 1 and 2 respectively.

In both of these constructions, which it is to be understood are given merely in illustration of the invention, the whirl velocity of the oil or other liquid fuel is varied by varying the width of a spiral duct through which the oil (preferably heated) is forced under pressure, the duct being formed by the coils of a helical spring which encircles the end of the regulating spindle whereby the rate of fuel consumption is controlled.

In the construction of Fig. 1, the helical spring A encircles the outer end of the regulating spindle C so as to slide freely thereon and is compressed between a tubular spindle D and a tubular abutment or seating B which also forms the wall of the whirl chamber leading to the discharge aperture S in the nozzle plate F. This plate has a rearwardly extending cylinder within which the seating B and the helical spring A fit snugly and which is itself encircled by the forward end of a hollow casting or shell G which forms an oil chamber E around the rear end

of the helical spring A and is screwthreaded internally at its rear end to receive an externally screwthreaded portion of the tubular spindle D, the rear end of which is also screwthreaded internally at P to receive a 60 screwthreaded portion of the regulating spindle C. The rear ends of the spindles C, D are each fitted with a hand-wheel or lever indicated at R, Q respectively whereby the coned end of the regulating spindle may be 65 advanced toward or withdrawn from the nozzle aperture S, and the helical spring A may have its spires compressed or released to vary the cross sectional area of the spiral duct M which imparts a gyratory or whirling motion to the oil which is delivered under pressure to inlet N in the casing K and passes thence through holes L in the inner casing or shell G into the chamber E. The shell G is flanged at its forward end to 70 abut against the end of the outer casing K and, together with the nozzle plate F, is secured by means of the cap H screwed on the end of the casing K. The cap H and plate F are coned to the same angle which as 75 shown is preferably somewhat greater than that of the cone of atomized fuel which issues from the burner. To prevent leakage of oil along the surface of the spindle C, the latter is preferably grooved circumferentially 80 at intervals along its length as indicated at T.

When the regulating spindle C is advanced so as to close the aperture S more or less, the tubular spindle D is rotated so as 90 to compress the spring A and reduce the whirling velocity of the oil to such an extent that the angle of the spray cone will remain constant. Similarly, when the regulating spindle C is withdrawn farther from the 95 aperture S, the tubular spindle D is unscrewed so as to increase the sectional area of the spiral duct M sufficiently to maintain the angle of the spray cone constant.

In the construction shown in Fig. 2 corresponding parts have been designated by the reference characters applied to those parts in Fig. 1, and the essential difference between the two constructions is that whereas in the former the two independently adjustable spindles were provided for controlling the rate of consumption and the whirl velocity of the fuel, both are simultaneously controlled in the construction of Fig. 2 by a single regulating spindle C 110

which has a collar W near its forward end forming the rear abutment of the helical spring A.

The relation of the aperture S, the coned end X of the regulating spindle, the collar W thereon and the rear edge of the cylindrical sleeve F' which extends rearwardly from the aperture plate F, is such that when the aperture S is on the point of being closed by the cone X the collar W abuts against the sleeve F', so that the spindle C may be screwed hard up by the handle R without damaging the edge of the aperture S.

15 It will be seen that with this construction as the coned end X of the regulating spindle is withdrawn from the aperture S, the helical spring A is simultaneously enabled to extend, thereby increasing the width of the 20 spiral duct M and consequently the whirl velocity of the oil. Conversely, when the regulating spindle is screwed toward the aperture S, the width of the spiral duct M is simultaneously and correspondingly decreased.

30 The rate of change of consumption of fuel and the rate of whirl velocity are so arranged that a constant or substantially constant angle of spraying cone will be maintained for all positions of the regulating spindle.

I claim—

35 1. In a liquid fuel burner, the combination of a fuel outlet, a whirl chamber behind said outlet, a regulating spindle projecting into said whirl chamber and a helical spring encircling said regulating spindle and forming a spiral duct through which the fuel is led to the whirl chamber.

2. In a liquid fuel burner, the combination 40 of a fuel outlet, a whirl chamber behind said outlet, a regulating spindle projecting into said whirl chamber, a helical spring encircling said regulating spindle and forming a spiral duct through which the fuel is 45 led to the whirl chamber and means for compressing said helical spring to vary the cross sectional area of the spaces between its several volutes.

3. In a liquid fuel burner, the combination 50 of a fuel outlet, a whirl chamber behind said outlet, a regulating spindle projecting into said whirl chamber, a helical spring encircling said regulating spindle and forming a spiral duct through which the 55 fuel is led to the whirl chamber and means operated by the regulating spindle to vary the cross sectional area of the spaces between the several volutes of said helical spring.

4. In a liquid fuel burner, the combination 60 of a fuel outlet, a whirl chamber behind said outlet, a regulating spindle projecting into said whirl chamber, a helical spring encircling said regulating spindle and forming a spiral duct through which the fuel is 65 led to the whirl chamber and means for compressing said helical spring to vary the cross sectional area of the spaces between its several volutes comprising a collar upon 70 the regulating spindle.

In testimony whereof I have signed my name to this specification in the presence of two subscribing witnesses.

HAROLD EDGAR YARROW. [L. S.]
